UNITED STATES PATENT OFFICE.

WILHELM F. ROHRS, OF BLACKWELL, OKLAHOMA.

DIRECTION-SIGNAL.

1,320,925.

Specification of Letters Patent.

Patented Nov. 4, 1919.

Application filed July 9, 1917. Serial No. 179,455.

To all whom it may concern:

Be it known that I, WILHELM F. ROHRS, a citizen of the United States, residing at Blackwell, in the county of Kay and State 5 of Oklahoma, have invented new and useful Improvements in Direction-Signals, of which the following is a specification.

This invention is a direction signal more especially designed for use in connection 10 with self-propelled vehicles, and more particularly for those vehicles in which it is inconvenient for the driver to indicate by a hand signal the various traffic signals required.

45 One object of the invention is to provide a signal which consists of few parts thus lessening the liability to derangement in use.

Another object is to provide a signal operable from the instrument board to indicate 20 all classes of signals, such signals being capable of being viewed from both the front and rear of the vehicle.

One practical form of construction and assembly will be described and illustrated in 25 the accompanying drawings, in which:—

Figure 1 is a rear elevation of a semaphore blade and its operating handle and the quadrant for the handle.

Fig. 2 is a perspective view of the quadrant or bracket.

In the preferred embodiment shown, the semaphore blade is indicated at 5. This blade is provided at its free end with tapering sides to form a cone-shaped end. Extending from the base of this cone-shaped portion the sides of the blade converge to a curved member 6. Adjacent the cone-shaped end, there is provided a light opening 7 in which may be positioned any suitable light emitting element. It is preferred to have transparent plates upon both sides of the blade so that the light may be viewed from the front and rear simultaneously. The blade may be formed of any suitable 40 material, such as hard wood or of light metal as may be desired.

The curved member 6 has secured to it at one end, in any convenient manner, the converging sides of the semaphore blade 5.

50 This member 6 is pivotally mounted upon a quadrant 8. The free or operating end of the curved member 6 is provided with a handle 9, and adjacent the handle 9 is a latch lifting handle 10, which is pivotally

mounted upon the curved member, as indicated at 11. The pivotal mounting for the curved member 6 relative to the quadrant is indicated at 12.

The quadrant 8 may be formed of any suitable material and carries upon its rounded edge suitable notches indicated at 13, 14, and 15. To coöperate with these notches there is provided a latch 16, which is coöperatively connected by a latch bar 17 to the latch handle 10. The quadrant 8 is preferably bolted to the instrument board by means of bolts, one of which is indicated at 19.

The quadrant shown in Fig. 1 is of the type that is more particularly adapted to be secured to a vertical instrument board, 70 while the type shown in Fig. 2 is for one that is positioned in a slanting direction. As shown in Fig. 2 this latter quadrant is provided with a suitable spacing flange 20, which is so formed that when the quadrant 75 is in its proper position relative to the board it will stand in a vertical direction. Suitable holes or apertures 21 and 22 are indicated for the purpose of bolting this quadrant to the instrument board 18.

In Fig. 1 the semaphore blade 5 is shown in a vertical or neutral position, at which time the latch engages with the notch 13. If it is desired to indicate that the vehicle will stop, the latch is withdrawn by means of 85 its handle 10, and the semaphore blade 5 by means of its handle 9 is moved to the next notch 15. Should it be desired to indicate that a left hand turn will be made, the curved member 6 is moved to the notch indicated 90 at 15, when the blade 5 will stand out approximately in a horizontal direction. Thus it will be seen that the various classes of signals or changes of direction may be readily indicated by the driver. The light 95 emitting means 7 may have any usual or customary type of connection with a suitable source of energy.

Minor changes in the form, proportion and details of construction may be resorted 100 to without departing from the spirit of the invention or the scope of the appended claims.

What is claimed is:—

In combination with the dash board of an 105 automobile, a quadrant having a flange thereon which is secured to the said board, a semaphore made of one piece of material

and consisting of a tapered blade, a handle extending at right angles from the blade and a curved part connecting said handle with the small end of the blade, a bolt passing through the center of said curved part and into the corner of said quadrant, said

quadrant having notches in its curved edge, a latch carried by the handle engaging said notches and a lifting handle pivoted to the handle and engaging with said latch.

10

In testimony whereof I affix my signature.

WILHELM F. ROHRS.
